UNITED STATES PATENT OFFICE.

MAXWELL F. MAY, OF PALOS PARK, ILLINOIS, ASSIGNOR TO DE REMER BLATCHFORD COMPANY, OF CHICAGO, ILLINOIS, A CORPORATION OF ILLINOIS.

FURNACE.

Application filed March 16, 1925. Serial No. 16,059.

This invention relates to a furnace for heating plates, billets, or other articles of the type comprising mechanism for intermittently raising the articles being heated from the floor of the furnace and carrying them forward step by step through the heating chamber. The present invention relates to improvements on the apparatus set forth and claimed in the patent granted to George P. White, No. 1,596,911, Aug. 24, 1926. In this type of apparatus, a carrier is provided which may be lowered into recesses in the floor of the furnace, whereby the articles are supported upon the furnace floor. Means is provided for elevating the carrier whereby the articles are lifted from the floor, subsequently the carrier, with the articles thereon, is moved longitudinally to carry the articles forward one step through the furnace, then the carrier is lowered to again lay the articles on the furnace floor, and then the carrier is moved back beneath the articles to its original position. Separate motor means are provided to impart the raising and lowering, and longitudinal movements to the carrier.

The principal object of this present invention is to provide automatically operating controlling connections between the source of power supply and the two motors for moving the carrier, whereby the motors will be successively operated in a predetermined order to move the carrier through a predetermined fixed path.

Another object is to provide means for imparting an initial movement to the controlling connections, whereby the carrier will be moved through one complete cycle and returned to its original position of rest.

Another object is to provide closures for the entrance and exit openings at the ends of the furnace, and motor means for operating these closures, which are so connected with the means for raising and lowering the carrier that the closures will be elevated or opened before the carrier is elevated and closed after the carrier is lowered.

Numerous other objects and advantages of this invention will be apparent from the following detailed description of one approved form of the apparatus.

In the accompanying drawings:

Fig. 1 is a front elevation of the furnace.

Fig. 2 is a transverse vertical section taken substantially on the line 2--2 of Fig. 3.

Fig. 3 is a longitudinal vertical section taken substantially on the line 3--3 of Fig. 1.

Fig. 4 is an enlarged detail view, partly in section, of one of the controlling valves for the translating motor.

Fig. 5 is a combination plan view and horizontal section, the upper portion of the figure being taken substantially on the line 5--5 of Figs. 2 and 3. Portions of the mechanism in the lower half of Fig. 5 are shown enlarged and diagrammatically arranged to facilitate the disclosure.

Referring to the drawings, 1 designates the floor of the furnace, which is formed with longitudinal slots or recesses 2 in which operate a portion of the mechanism for moving the plates, or other articles, through the furnace.

The side walls of the furnace shown at 3, are provided with tuyères 4 for the admission of fuel in the form of gas or oil for heating the interior of the furnace. The cover arch is shown at 5, 6 is the front wall provided with an opening 7 through which the articles are placed within the furnace, and 8 is the rear wall provided with an exit opening 9 through which the articles emerge from the furnace. A table for receiving the hot articles after they are carried from the furnace is indicated in dotted lines at 10, Fig. 3. The furnace, it will be understood, may be of any suitable construction, my invention being concerned principally with the mechanism for intermittently moving the plates, billets, or other articles, through the furnace.

The conveyor mechanism comprises a carrier, preferably consisting of a number of longitudinally arranged pipes 11 extending through the slots 2 in the floor of the furnace, and connected together at their ends, outside of the furnace, by cross-beams 13, and by header pipes 12 provided with flexible hoses for circulating water through the carrier structure, so that the metallic pipes 11 may withstand the rather intense heat within the furnace. The carrier is supported, slidably, on a pair of transverse members 14, one at each end of the furnace, which members are movable vertically in channel guides 15 and are furnished with rollers 16, preferably of the concave type, on which are supported the pipes 11. The transverse members 14, which are shown

as I-beams, are suspended by straps 17 from links 18, the upper ends of which are pivoted to the arms 19 of bellcranks 20 fixed to rock shafts 21, mounted in bearings 22 at the top 5 of the furnace structure. It will be understood that one of the bellcranks 20 is secured near either end of each rock shaft 21, which extends transversely across the furnace. The upstanding arms 23 of the 10 bellcranks are connected by links 24, so that all of the bellcranks turn in unison to raise both ends of both of the transverse members 14 simultaneously. A third arm 25 on one of the rock shafts 21 is connected by means 15 of a downwardly extending link 26 with a fluid pressure operated motor A. As here shown the motor A is in the form of a fluid pressure cylinder 27 in which operates a piston connected by piston rod 28 with the 20 link 26.

The carrier 11 is moved forwardly while in its elevated position, and in the opposite direction or backwardly when lowered into the floor recesses 2 by means of a second fluid 25 pressure operated motor B. The motor B comprises a double acting fluid pressure cylinder 29, in which operates a piston 30 connected by piston rod 31 to a lever 32, the lower end of which has a slotted pivoted connection 33 with an anchorage 34, and the upper end of which has a similar pin and slot connection 35 with a bracket 36 on the carrier 11. The connection 35 comprises a rather long slot 37 in the lever 32 in which 30 operates a pin or roller 38 carried by the bracket 36. The increased length of slot 37 is to make provision for the raising and lowering of the carrier and for its longitudinal movements at both levels.

40 In the operation of the mechanism as thus far described, and with the parts in the initial position shown in the drawings, motor A will be operated to move the piston rod 28 downwardly, thereby through link 26 45 swing the bellcranks 20 and elevating the carrier structure 11 by means of the links 18. The operating lever 32 being in the inclined position shown in Fig. 3, the engagement of pin or roller 38 with slot 37 will cause the 50 carrier 11 to move diagonally upward until the pipes of the carrier lift the articles formerly resting upon the floor 1 of the furnace. Motor B will now be operated to draw the piston rod 31 into the cylinder 29 thereby 55 swinging operating lever 32 over to the other side of its fulcrum 33 and moving the pipes 11 and the articles carried thereby longitudinally through the furnace toward the rear end thereof, the pipes 11 moving freely 60 over the rollers 16 on supporting means 14. The pressure fluid is now exhausted from the cylinder 27 of motor A and the carrier is moved by gravity into the recesses 2 of the furnace floor, depositing the articles on the 65 floor but each at a point a step in advance

of its former position. Double acting motor B is now operated to swing the lever 32 back to the position indicated in Fig. 3, thereby translating the pipes 11 in the opposite direction along the supporting rollers 16 until 70 they are again in the position in which they were found at the beginning of the cycle of operations just described. During this final translating movement the pipes 11 move in the slots or recesses 2 beneath the articles in 75 the furnace, but out of contact therewith, so that no movement is imparted to the articles. By successively imparting, at desired intervals of time, to the carrier 11 the 80 cycle of movements just described, the articles inserted into the furnace through the front opening 7 are gradually moved step by step through the furnace until they emerge through the rear exit opening 9 onto the delivery table 10. All of the mechanism thus far described is substantially the 85 same as disclosed in greater detail and claimed in the patent to White, noted hereinabove.

In order to conserve heat and provide 90 more even temperature conditions within the furnace, it is desirable that the openings 7 and 9 in the ends of the furnace be closed as much of the time as possible. For this purpose, I have provided closures 39, here 95 shown as a plurality of vertically slideable gates or blocks 40, connected by a frame structure 41 to move vertically in unison in front of the opening 7 or 9. The closures at each end of the furnace are substantially 100 identical, and a description of one will suffice for both. The central panel of the closure 39 is suspended from one end of a chain or cable 42 extending over guide rollers 43 and 44 at the top of the furnace structure 105 and carrying at its other end a counter-weight 35. A second looped cable or chain 46 has its ends connected at 47 to the two end panels 40 of the closure, the chain passing over guide rollers 48, 49 and 50 and carrying 110 in its downwardly extending loop a roller 51 by means of which is suspended the counter-weight 52, connected to the upper end of a piston rod 53 of a fluid pressure operated 115 motor C or C', the two motors C and C' being identical and one operating each of the two closures 39. When fluid under pressure is admitted to the cylinders 54 of the motors C and C', piston rods 53 will be drawn 120 downwardly and through the chain or cable 46 will elevate the closures 39. When the fluid pressure is exhausted from the cylinders 54, the closures 39, which somewhat outweigh the counter-weights 45 and 52, will return by gravity to their initial positions closing the openings 7 and 9.

It will be noted from Fig. 5 that the pipe 125 55 which supplies fluid under pressure to the cylinder 27 of the lifting motor A, has an extension 56 leading to the cylinders 54 130

of the closure operating motors C and C'. The numeral 57 indicates throttle valves in the feed pipes leading to the cylinders 54, these throttle valves being normally fully open. Another throttle valve 58 is positioned in the feed pipe leading to the cylinder of motor A, and this throttle valve will be partially closed so as to restrict the flow of fluid under pressure to the cylinder 27. 10 The purpose of this is to cause the motors C and C' to operate more promptly than the motor A, so that when fluid under pressure is simultaneously supplied through pipe 55 to these three motors, the closures 39 will be raised somewhat more rapidly than the carrier 11, thus avoiding any interference between these parts and permitting the carrier pipes to be lifted up into the openings 7 and 9 and out of the slots or recesses 2.

20 I have provided a series of valves and connections whereby the motors A and B are successively operated in a predetermined order to impart a cycle of movements to the carrier 11, whereby it is moved through the closed path or orbit hereinabove described. These automatic controlling connections comprise a valve means D for controlling lifting motor A, and a pair of cooperating valve means E and F for controlling the translating motor B. A manually operated master valve or controller G is designed to initiate the automatic cycle of operations whenever a movement of the articles through the furnace is thought to be desirable. The master controller G might be operated mechanically, by any suitable mechanism, to cause the operation of the carrier at regular intervals of time.

As shown in Fig. 5, controller G is in the form of an ordinary three-way valve provided with an operating handle 59. One pipe connection 60 extending from valve G leads to the main fluid pressure supply pipe 61. Pipe 61 is in constant communication with any suitable source of fluid under pressure. The opposite pipe connection 62 of valve D is open to the air to serve as an exhaust vent. The intermediate pipe connection 63 leads to the cylinder 64 of a small fluid pressure motor carried by bracket 65, and having an operating piston 66. When valve D is in the normal position shown in Fig. 5, the port 67 in the valve will connect pipe 63 with exhaust 62 so that cylinder 64 is open to normal atmospheric pressure. In order to initiate a cycle of movements of the carrier, cam lever 59 is momentarily moved to the dotted line position (Fig. 5) and then returned to its original full line position. While moved to the dotted line position, pipe 63 will be temporarily in communication through pipe 60 with the source of fluid supply, and the pressure thus delivered to cylinder 64 will push out the piston 66.

The outer end 67^a of piston 66 bears against one arm 68 of a bellcrank lever, the other arm 69 of which has a pin and slot connection 70 with the piston rod 71 extending from the piston 72 of the valve 70 D. Cylinder 73 of valve D has inlet ports 74 and 75 adjacent either end thereof, these ports being connected through pipes 76, 77 and 78 with the main supply pipe 61. In this way the valve D is balanced by a constant supply of equal fluid pressure against each end of the piston 72. The central portion of piston 72 is cut away to provide an annular space 79 which is always in communication with an exhaust port 80 in one side of cylinder 73. The supply pipe 55 for the lifting motor A and the closure operating motors C and C', communicates with port 81 in one side of valve cylinder 73. When valve D is in the position indicated in Fig. 5, supply pipe 55 is in communication with the annular space 79 in piston 72, and thence in communication with exhaust port 80, whereby the cylinders of motors A, C and C' are exhausted by being open to the atmosphere. When the master control valve G is operated, as hereinabove described, to momentarily admit fluid pressure into the cylinder 64, the movements thus imparted to piston 66, bellcrank 68 and 69, and piston rod 71, will move the piston 72 to the left, Fig. 5, into the dotted line position, so that pipe 55 is now cut off from the exhaust 80 but is in communication with the main supply pipe 61, through pipes 78, 77, 75 and port 81. Fluid under pressure will now be admitted directly to the cylinders of motors A, C and C', whereupon the closures 39 will first be elevated, directly followed by the carrier 11.

Referring now more particularly to Figs. 3 and 4, it will be noted that the controlling valve E for the translating motor B is of much the same type as valve D previously described. A continuation of the main fluid pressure supply pipe 61 is in communication through branches 82 and 83, with the inlet ports 84 and 85 near either end of the valve cylinder 86, whereby the pressure against the ends of piston 87 is substantially balanced at all times. A pipe 88 is in communication with one outlet port 89 near one end of the cylinder 86, and another pipe 90 is in communication with a similar outlet port 91 near the other end of the cylinder. An exhaust port 92 arranged centrally in one wall of cylinder 86 is in constant communication with the annular space 93 formed by cutting away the central portion of piston 87. Pipe 90 leads to the inlet port 120 at the far end of cylinder 29 of translating motor B, and with the parts in the positions shown in the drawings there is a free passage for fluid under pressure from supply pipe 61 through pipe 83, inlet port 85, 130

4

cylinder 86, outlet port 91, pipe 90 to motor cylinder 29, so that the fluid pressure is bearing against the rear face of piston 30 and holding the piston rod 31 extended and lever rod 32 in the position indicated in Fig. 3. Pipe 88 leads to one port 94 of the ordinary four-way valve F. The pipe 95 leads from another port 96 of this valve F to the opposite inlet port of cylinder 29 of motor B. The third port 97 of valve F, opposite port 94, is in communication with an exhaust pipe 98. The fourth port is preferably closed by a plug 99 as shown in Fig. 5. The oscillatable inner body portion 100 of the valve F is provided with two arcuate cutaway portions 101 and 102, and with the valve in the position indicated in Fig. 5, the cutaway portion 101 places pipes 88 and 95 in communication with one another. When valve body 100 is rocked into the dotted line position, the cutaway portion 102 places pipe 95 into communication with the exhaust 98. With the parts in the position shown in the drawings, the front end of cylinder 29 of motor B is exhausted to atmospheric pressure through pipe 95, valve F, pipe 88, annular space 93 and exhaust port 92 of valve E.

An arm 103 projects laterally from one side of the link 26 of lifting motor A, and this arm 103 is connected through link 104 with a vertical slide rod 105 operating through guides 106 and 107 projecting from a portion of the fixed framework. A piston rod 108 projects upwardly from the piston 87 of valve E, and a forked arm 109 projecting laterally from this piston rod 108 embraces the slide rod 105 between a pair of spaced stops 110 and 111 secured adjustably to the rod 105. When motor A is operated to elevate the carrier 11, link 26 will be moved downwardly, thereby pushing down the slide rod 105, and near the end of this movement stop 111 will engage the forked arm 109 and through piston rod 108 shift the piston 87 into the lower dotted line position indicated in Fig. 4. This movement of the piston 87 will cut off the pipe 90 from communication with the fluid pressure supply and place this pipe in communication with the exhaust port 92, thereby exhausting the rear end of cylinder 29 of motor B. At the same time pipe 88 leading to the other end of cylinder 29 of motor B will be placed in communication with the supply pipe 61 through pipe connections 82 and ports 84 and 89. Fluid pressure thus being delivered against the other or front side of piston 30, the motor B will operate to swing the operating lever 32 to the other end of its arc of travel thereby translating the pipes 11 (which are now elevated and supporting the articles within the furnace), rearwardly one step through the furnace.

An arm 112 projects laterally from the end of piston rod 31 of motor B, and the free end of this arm loosely surrounds a slide rod 113, slidably through fixed bearings 114. As the piston rod 31 is drawn into the cylinder 29 during the translating movement of motor B just described above, the arm 112 will engage an adjustably fixed stop 115 on slide rod 113 and draw this rod 113 along in the same direction as the translating movement of the piston rod 31 and carrier 11. Slide rod 113, which is made in sections connected by a safety spring 116, is pivoted at its end 117 to the fulcrum of a bellcrank lever, one arm 119 of which is pivoted to the operating crank arm 120 for the rocking body portion 100 of valve F. A spring 121 connected at one end to the crank arm 120 and at the other end to an adjustable anchorage 122, normally holds the valve F in the position indicated in Fig. 5. The second arm 123 of the bell crank is engaged with a slide block 124 loosely mounted on a link or rod 125, which is pivoted at one end 126 to a third arm 127 projecting from the bell crank which operates the slideable piston of the control valve D for the lifting motor A. As slide rod 113 is moved rearwardly by the piston rod 31 of motor B, the bell crank arm 123 will move the slide block 124 into engagement with a spring 128 confined on rod 125 in front of a stop 129 at the free end of this rod. This pull of the rod 125 will swing the bell crank 127, 69 and move the piston 72 of valve D back to the full line position indicated in Fig. 5. At the same time the other arm 119 of the movable bellcrank will, through crank arm 120, swing the valve body 100 of valve F into the dotted line position placing pipe 95 in communication with the exhaust 98 and stopping the flow of fluid from pipe 88 to cylinder 29. Pipe 55 is now in communication with the exhaust port 80, and the carrier 11, and the closures 39, will sink by gravity to their lowered positions. The articles carried by the pipes 11 will again be laid upon the floor 1 of the furnace, but in positions advanced one step toward the rear of the furnace from their former positions.

As the carrier 11 moves downwardly, the rod 105 will be drawn up until stop 110 engages the arm 109 and the piston 87 is shifted back to its original full line position as shown in Fig. 4. This again places pipe 90 in communication with the main supply pipe 61, and fluid pressure is again delivered to the rear end of motor D, and since the front end of this cylinder is in communication through pipe 95 with one exhaust port 98, the piston 30 will be moved back toward the left, (Fig. 3), thereby returning the carrier pipes 11, which are now nested within the slots 2 of the furnace 4, 130

back to their original positions as shown in full lines (Fig. 3). This movement of piston rod 31 will release the arm 112 from engagement with the adjustable stop or collar 115 of rod 113, and the spring 121 will then swing the crank 120 and valve body 100 back to the original solid line positions, as shown in Fig. 5. The stop collar 115 is made adjustable, it will be understood, so that the inward stroke of the piston 30, and consequently the length of travel of the articles through the furnace at each cycle of operations, may be varied. That is by shifting valve body 100 earlier or later, which will depend on the position of collar 115 on rod 113, air pressure may be cut off from the translating cylinder 29 at different points in the travel of piston 30 so as to vary the length of the movement of the articles through the furnace as may be desired.

This completes one cycle of operations, and it will be noted that all of the moving parts have been returned to their original positions, which they occupied before this series of movements was initiated by the manipulation of master control valve G. It will be noted that after the first manual manipulation of the handle 59 of valve G, which requires no especial skill whatever, the operation of the apparatus is entirely automatic until one complete cycle of movements have been completed. Obviously any suitable timing mechanism might be employed to actuate the valve G at desired intervals, thus rendering the operation of the apparatus entirely automatic but such operation is not preferred for large articles especially since it is best to have some skilled operator to determine the length of the periods between forward movements of the articles through the furnace so as to discharge the articles at the proper temperature. By means of the preferred apparatus shown, the moving parts of the conveyor mechanism come to a stop automatically after each cycle of operations and remains stationary until reactivated by manual operation of the master valve G.

I claim:

1. In combination with a furnace, mechanism for moving bodies intermittently through the furnace comprising a carrier, means for raising and lowering the carrier, means for imparting longitudinal movements to the carrier alternately in opposite directions, means whereby the amplitude of said longitudinal movement may be varied, and a single controlling means for actuating the two first mentioned means in a predetermined order.

2. In combination with a furnace, mechanism for moving bodies intermittently through the furnace comprising a carrier, means for raising and lowering the carrier, means for imparting longitudinal movements to the carrier alternately in opposite

directions, and a fluid pressure actuated controlling means comprising a manually operable valve for causing the successive operation of the two first mentioned means so as to impart a predetermined cycle of movements to the carrier.

3. In combination with a furnace, mechanism for moving bodies intermittently through the furnace comprising a carrier, means for raising and lowering the carrier, means for moving the carrier longitudinally in one direction when the carrier is raised, and for moving it longitudinally in the opposite direction when lowered, and controlling means adapted to be actuated by hand for causing the operation of the two first mentioned means in such order that the carrier will be moved through a predetermined closed path and will then remain stationary until the controlling means is again actuated.

4. In combination with a furnace, mechanism for moving bodies intermittently through the furnace comprising a carrier, means for raising and lowering the carrier, means for moving the carrier longitudinally in one direction when the carrier is raised, and for moving it longitudinally in the opposite direction when lowered, and controlling means comprising a member movable at will of the operator for causing the operation of the two first mentioned means in such order that the carrier will be moved once through a predetermined closed path and will then be stopped when in its initial position and remain stationary until the controlling means is reactivated by another movement of said movable member.

5. In combination with a furnace, mechanism for moving bodies intermittently through the furnace comprising a carrier, motor means for raising and lowering the carrier, motor means for imparting longitudinal movements to the carrier, means whereby the amplitude of said longitudinal movements may be varied, a source of power for energizing the motors, and controlling connections between the source of power and the motors whereby the motors will be successively operated to move the carrier through a predetermined closed path.

6. In combination with a furnace, mechanism for moving bodies intermittently through the furnace comprising a carrier, motor means for raising and lowering the carrier, motor means for imparting longitudinal movements to the carrier, a source of power for energizing the motors, controlling connections between the source of power and the motors, and means comprising a controlling member movable at will of the operator for effecting a single cycle only of movements of these connections whereby the motors will be successively operated to move the carrier through a predetermined closed

path and return it to the original position of rest.

7. In combination with a furnace, mechanism for moving bodies through the furnace comprising a carrier, means for raising and lowering the carrier, separate means for translating the carrier, means whereby the amplitude of the translating movements of the carrier may be varied and controlling connections for actuating the elevating and translating means in such a predetermined order as to impart a definite cycle of movements to the carrier.

8. In combination with a furnace having entrance and exit openings, fluid pressure operated means for moving bodies intermittently through the furnace, closures for said openings, fluid pressure operated means for moving said closures away from said openings, a source of supply of fluid under pressure, supply pipes therefrom to said fluid pressure operated means, and retarding means in the pipe leading to the fluid pressure means for moving the bodies through the furnace.

9. In combination with a furnace, mechanism for moving bodies intermittently through the furnace comprising a carrier, a fluid pressure operated means for raising and lowering the carrier, a second fluid pressure operated means for moving the carrier longitudinally in one direction when elevated and in the opposite direction when lowered, means whereby the amplitude of said longitudinal movements may be varied, a source of fluid under pressure, and a system of valves for causing the successive operation of the two pressure operated means to impart a predetermined cycle of movements to the carrier.

10. In combination with a furnace, mechanism for moving bodies intermittently through the furnace comprising a carrier, a fluid pressure operated means for raising and lowering the carrier, a second fluid pressure operated means for moving the carrier longitudinally in one direction when elevated and in the opposite direction when lowered, a source of fluid under pressure, a system of valves for causing the successive operation of the two pressure operated means in a predetermined order, and a master control valve for initiating a series of operations of the valves and pressure operated means whereby one complete cycle of movements only is imparted to the carrier.

11. In combination with a furnace, mechanism for moving bodies intermittently through the furnace comprising a carrier, a fluid pressure operated motor for raising and lowering the carrier, valve means for controlling the operation of this motor, a second fluid pressure operated motor for moving the carrier longitudinally in one

direction when elevated and in the opposite direction when lowered, valve means for controlling this second motor, a source of fluid under pressure, and means momentarily operated for imparting an initial movement to the first mentioned valve means, whereupon the valves and motors are successively operated to move the carrier through a single cycle of movements and return it to the first position of rest.

12. In combination with a furnace, mechanism for moving bodies intermittently through the furnace comprising a carrier, a fluid pressure operated motor for raising and lowering the carrier, valve means for controlling the operation of this motor, a second fluid pressure operated motor for moving the carrier longitudinally in one direction when elevated and in the opposite direction when lowered, valve means for controlling this second motor, a source of fluid under pressure, fluid pressure operated means for imparting an initial movement to the first mentioned valve means for causing the first motor to elevate the carrier, and connections between the carrier elevating means and the second mentioned valve means for causing a longitudinal movement of the carrier after it is elevated.

13. In combination with a furnace, mechanism for moving bodies intermittently through the furnace comprising a carrier, a fluid pressure operated motor for raising and lowering the carrier, valve means for controlling the operation of this motor, a second fluid pressure operated motor for moving the carrier longitudinally in one direction when elevated and in the opposite direction when lowered, valve means for controlling this second motor, a source of fluid under pressure, fluid pressure operated means for imparting an initial movement to the first mentioned valve means for causing the first motor to elevate the carrier, connections between the carrier elevating means and the second mentioned valve means for causing a longitudinal movement of the carrier after it is elevated, connections operated by the second mentioned motor for moving the first mentioned valve means to lower the carrier, the first mentioned connections operating when the carrier is lowered to move the second mentioned valve means whereby the carrier is moved back longitudinally to its original position of rest.

14. In combination with a furnace having a recessed floor, mechanism for moving bodies intermittently through the furnace comprising a carrier which, when out of engagement with the bodies is lowered within the floor recesses, means for lifting the carrier from the recesses into engagement with the bodies, means for translating the carrier with the bodies when elevated, and for returning the carrier when lowered to its

original position, and means adapted to be made operative only momentarily to control the successive operations of the two first mentioned means so as to impart a single cycle of movements only to the carrier.

15. In combination with a furnace having a recessed floor, mechanism for moving bodies intermittently through the furnace comprising a carrier which, when out of engagement with the bodies is lowered within the floor recesses, means for lifting the carrier from the recesses into engagement with the bodies, means for translating the carrier with the bodies when elevated, and for returning the carrier when lowered to its original position a manually movable controlling member, and a series of cooperating connections for causing the successive operation of the two first mentioned means in such an order as will move the carrier through one complete cycle only and advance the bodies one step through the furnace.

20. In combination with a furnace having a recessed floor, mechanism for moving bodies intermittently through the furnace comprising a carrier which, when out of engagement with the bodies is lowered within the floor recesses, a fluid operated motor for lifting the carrier from the recesses into engagement with the bodies, a second fluid operated motor for translating the carrier with the bodies when elevated, and for returning the carrier when lowered to its original position a manually movable controlling member, and a series of cooperating valves for causing the successive operation of the motors in such an order as will move the carrier through one complete cycle only and return it to the original position.

25. In combination with a furnace having a recessed floor, mechanism for moving bodies intermittently through the furnace comprising a carrier which, when out of engagement with the bodies is lowered within the floor recesses, a fluid operated motor for lifting the carrier from the recesses into engagement with the bodies, a second fluid operated motor for translating the carrier with the bodies when elevated, and for returning the carrier when lowered to its original position, a series of valves for controlling the motors, and fluid pressure means for operating said valve whereby the motors will be successively operated to impart a predetermined cycle of movements to the carrier.

30. In combination with a furnace having a recessed floor, mechanism for moving bodies intermittently through the furnace comprising a carrier which, when out of engagement with the bodies is lowered within the floor recesses, a fluid operated motor

for lifting the carrier from the recesses into engagement with the bodies, a second fluid operated motor for translating the carrier with the bodies when elevated, and for returning the carrier when lowered to its original position, a series of valves for controlling the motors, automatically operating connections between the valves and moving parts of the apparatus, and a manually operated means for imparting an initial movement to the controlling connections whereupon the motors will be successively operated in a predetermined order to impart one complete cycle of movements only to the carrier, moving it through a predetermined closed path and returning it to the starting position.

19. In combination with a furnace, mechanism for conveying bodies through the furnace by step by step movements, closures for the entrance and exit openings of the furnace, and automatic means comprising a controlling member movable at the will of the operator, which when moved effects a single series of operations, consisting in the movement of the closures away from said openings, a single forward movement of the bodies through the furnace and the movement of the closures across said openings.

20. In combination with a furnace, a carrier, a fluid pressure lifting cylinder for the carrier, a fluid pressure translating cylinder for the carrier, a valve F to control the flow of fluid to one end of the translating cylinder, a valve E to control flow of fluid to the other end of the translating cylinder and to valve F, a valve D for controlling the flow of fluid to the lifting cylinder, a fluid pressure motor for shifting valve D in one direction, said valve D being moved in the other direction by the piston of the translating cylinder, a valve G for controlling the flow of fluid to the fluid pressure motor, and means actuated by the movement of the piston of the lifting cylinder for shifting valve E.

21. In combination with a furnace, a carrier, a fluid pressure lifting cylinder for the carrier, a fluid pressure translating cylinder for the carrier, a valve F to control the flow of fluid to one end of the translating cylinder, a valve E to control the flow of fluid to the other end of the translating cylinder and to valve F, a valve D for controlling the flow of fluid to the lifting cylinder, a fluid pressure motor for shifting valve D in one direction, said valve D being moved in the other direction by the piston of the translating cylinder, a valve G for controlling the flow of fluid to the fluid pressure motor, means actuated by the movement of the piston of the lifting cylinder for shifting valve E, a door, a lifting cylinder for the door, supply pipes leading to the two

lifting cylinders, and a throttle valve in the pipe leading to the lifting cylinder for the carrier.

22. In combination with a furnace open at either end, closures for these openings, a fluid pressure operated motor for opening and closing the closures, mechanism for moving bodies intermittently through the furnace from one end to the other comprising a carrier, a fluid pressure operated motor for raising and lowering the carrier when the closures are open, a fluid pressure operated motor for imparting longitudinal movements to the carrier in one direction when elevated and in the opposite direction when lowered, and a fluid pressure operated means for controlling the different motors whereby the closures will be moved to open position before the carrier is elevated, and will be closed after the carrier is lowered.

23. In combination with a furnace open at either end, closures for these openings, motor means for operating the closures, mechanism for moving bodies intermittently through the furnace comprising a carrier, motor means for raising and lowering the carrier, and operating connections between the two motor means whereby the closures will be moved to open position before the carrier is elevated, and will be closed after the carrier is lowered.

24. In combination with a furnace open at either end, closures for these openings,

fluid pressure operated motor means for moving the closures, mechanism for intermittently moving bodies through the furnace comprising a carrier, fluid pressure operated motor means for raising and lowering the carrier, a common supply pipe for the two motor means, valve means for controlling the flow of fluid under pressure to the motors, and means for restricting the flow of fluid to the raising and lowering motor whereby the closure will be opened before the carrier is elevated.

25. In combination with a furnace open at either end, closures for these openings, motor means for operating the closures, mechanism for moving bodies intermittently through the furnace from one end to the other comprising a carrier, motor means for raising and lowering the carrier when the closures are open, motor means for imparting longitudinal movements to the carrier in one direction when elevated and in the opposite direction when lowered, and fluid pressure operated means for controlling the different motor means whereby when a cycle of movements is initiated the closures will be opened, the carrier raised, moved longitudinally in one direction and then lowered, the closures returned to closed position, and the carrier returned longitudinally to its original position of rest.

MAXWELL F. MAY.

Certificate of Correction.

Patent No. 1,615,197.

Granted January 18, 1927, to

MAXWELL F. MAY,

It is hereby certified that error appears in the printed specification of the above-mentioned patent requiring correction as follows: Page 4, line 126, for the word "one" read *the*; and that the said Letters Patent should be read with this correction therein that the same may conform to the record of the case in the Patent Office.

Signed and sealed this 8th day of March, A. D. 1927.

[SEAL.]

M. J. MOORE,
Acting Commissioner of Patents.
